United States Patent Office.

NEWELL TUPPER, OF GRAND BLANC, MICHIGAN.

Letters Patent No. 84,321, dated November 24, 1868.

IMPROVEMENT IN ADJUSTABLE FLOOD-GATES.

The Schedule referred to in these Letters Patent and making part of the same.

To whom it may concern:

Be it known that I, NEWELL TUPPER, of Grand Blanc, in the county of Genesee, and State of Michigan, have invented a new and useful Improvement in Adjustable Water-Gates; and I do declare that the following is a true and accurate description thereof, reference being had to the accompanying drawings, and to the letters of reference marked thereon, and being a part of this specification.

In the drawing, A represents the ground and bed of a stream, into which are firmly set the perpendicular posts B. The braces C are intended to be fastened to the posts B, and, extending to the ground, may be secured in any suitable way, to secure the posts B in an upright position.

From the top of the posts B are suspended, in a diagonal position with relation to the said posts, the rods O, at their outer ends engaging with the link or ring D, to which are also attached the arms E, the opposite ends of which are rigidly attached to the posts B, the whole forming a support from which to suspend, by any proper device, the gates F, which are composed of parallel bars G, held in position relative to each other by perpendicular rods or bars H, or any other suitable device.

In the drawing, the two lower bars are rigidly attached to each other, and then hinged at I, to the suspending-rods which hold the upper bar, and attach the same to the arms.

J are proper hooks attached to the arms, and are used to fasten the lower part of the gate when folded up, as shown upon the left of the drawing, to the arms.

The object of this invention is to so construct a gate, to be used as a continuation of a fence, across streams, that, hanging loosely from the suspending-arms, will allow drift-wood and other floating substances to pass off, and that can, in high water, when ice is running, be folded up and secured, as shown in the drawing, thereby preventing the gate from being injured or carried away.

What I claim as my invention, and desire to secure by Letters Patent, is—

The combination of the parts C D E G H I J, in a water-gate, substantially as and for the purposes set forth.

NEWELL TUPPER.
